UNITED STATES PATENT OFFICE.

EDMUND O. SCHWEITZER, OF CHICAGO, ILLINOIS.

ADAPTER FOR ELECTRICAL FIXTURES.

Application filed September 9, 1920. Serial No. 409,195.

To all whom it may concern:

Be it known that I, EDMUND O. SCHWEITZER, a citizen of the United States, residing at Chicago, in the county of Cook and State of Illinois, have invented a certain new and useful Improvement in Adapters for Electrical Fixtures, of which the following is a full, clear, concise, and exact description, reference being had to the accompanying 10 drawings, forming a part of this specification.

My invention relates to adapters for electrical fixtures. The present invention is a development of the inventive conceptions 15 disclosed in my co-pending applications Serial No. 294,721, filed May 5th, 1919, and Serial No. 340,238, filed November 24, 1919.

The present form of adapter has been particularly devised to enable a number of 20 electrical devices to be electrically connected to a single service outlet. For example, it is frequently desirable to operate a number of lamps, or both a lamp and a toaster, a lamp and a sewing machine motor, or such units 25 in a room where only a single outlet is convenient to both units. The general practice heretofore in such circumstances has been to employ a multiple socket connecting member in the form of a plug having a plurality of 30 sockets mounted in the plug, this socket member being commonly known as a "Benjamin cluster". This type of connector is generally unsuitable for use in the lighting fixtures of a residence, etc., owing partic- 35 ularly to the inability to adapt the connector to the various lighting schemes desired, and also owing to the inartistic appearance of the connector. That is to say, where a direct lighting effect is desired, with each 40 bulb arranged vertically for uniform distribution of the light, this type of connector is entirely incapable of adaptation to these requirements; or where an indirect lighting effect is desired in combination with an indi- 45 rect shade or reflector it is similarly incapable of adaptation to these requirements. Furthermore, this type of connector is devoid of any artistic configuration, and can- 50 not be harmoniously employed with the ornamental fixtures of a residence, etc.

The present form of adapter has been devised to provide a converting unit by which any direct lighting fixture may be readily converted into an indirect lighting fixture 55 by the mere screwing of the unit into the direct lighting fixture socket. The adapter is

constructed to readily accommodate any shade or reflector which may have been previously used for direct lighting effects, so that in making such a conversion all that it is necessary to do is to insert the adapter in the fixture socket and mount the direct lighting shade or reflector on the adapter in inverted relation, whereby an indirect lighting effect is secured without requiring any new or different style of shade or reflector. Any other preferred shade or reflector may, of course, be substituted for the original shade or reflector. For example, I contemplate employing with my 70 improved adapter a particular combination of two shades or reflectors for first diffusing the light and then softening it, this being secured through the cooperative relation of the two shades. 75

In accordance with the above aim, the primary object of the present invention is to provide an improved construction of adapter for connecting a light and an attachment circuit to a single outlet socket, 80 which adapter will permit the light to assume the proper angle with respect to the electrical fixture, and will also permit of the various adaptations in direct or indirect lighting schemes. 85

A secondary object is to devise a form of adapter which will be of simple and attractive design for use with all classes of lighting fixtures, particularly where it is essential that the artistic or æsthetic aspect 90 of the fixture be unimpaired.

A further object is to provide a construction of multiple socket for the present adapter in which the socket contacts are arranged to perform a switching function for 95 one of the sockets, this switching function being arranged for control by a conventional form of a plug member in the cooperating socket.

Another object is to provide a construction of adapter built up largely of standard plug and socket members, whereby the adapter may be cheaply and conveniently manufactured. 100

Further objects incident in the particular construction and arrangement of the contacts and other parts of the structure will be hereinafter apparent in the specification taken in connection with the accompanying drawings in which I have illustrated a preferred embodiment of my invention. 105 110

Referring to the drawings:

Figure 1 is a side elevational view with parts in section, illustrating an indirect lighting adaptation;

5 Figure 2 is an elevational view illustrating a direct lighting adaptation with the adapter supported in a diagonal socket;

10 Figures 3 and 4 are vertical sectional views through the plug and socket ends of the adapter respectively;

Figure 5 is a transverse sectional view thru the combined lighting and attachment sockets on the line 5—5 of Fig. 4;

15 Figure 6 is an elevational view, with parts in section, of a slightly modified construction of adapter;

Figure 7 is an elevational view of another modified construction of adapter;

20 Figure 8 is an elevational view, with parts in section, of still another modified form of adapter;

Figure 9 is a transverse sectional view taken approximately on the plane of a line 9—9 of Figure 6.

25 Figures 10 and 11 are side and front elevational views respectively of a hinge type of depending arm adaptable to either of the above constructions;

30 Figure 12 is a side elevational view of an extensible type of depending arm, also adaptable to either of the above constructions.

Figure 13 is a reduced elevational view illustrating the combined grouping of a reflector and shade on the adapter for the purpose of producing a soft, diffused, indirect light.

35 The form of adapter illustrated in Figures 1 and 2 comprises a plug member 12 which is adapted to be screwed into the outlet socket 13 of a conventional form of lighting fixture. I have shown the standard Edison type of plug and socket as being the preferred form because of certain advantages which can be secured by the same.

40 Pivotedly supported on the bottom of the plug 12 and depending therefrom is a tubular supporting arm 14 of curved goose-neck formation. The tubular arm 14 carries at its lower end the combined light and attachment

45 sockets 15 and 16, the latter socket forming a terminal connection for the appliance circuit. These sockets comprise two concentric portions, namely, the outer shell or ring and a central stud or plate as is well

50 understood by those skilled in the art. This tubular arm preferably consists of a section of brass tubing which is flattened in the curved portion intermediate the plug 12 and sockets 15—16 so as to present a minimum

55 thickness of tube to the rays from the light 17 and thereby reduce the extent of shadow cast by the tubular arm. As shown in Figure 3, the horizontal pivotal portion 18 of the tube is formed cylindrical, and is provided with two collars 19 and 20. I con-

template as the preferred construction the employment of a standard construction of plug 12, modifying this construction of plug only to a slight degree in adapting it to the present construction. The under face of the 70

plug member 12 is grooved transversely as indicated at 22 to accommodate the cylindrical portion 18 of the tubular arm, the two collars 19 and 20 embracing the sides of the body portion of the plug. The cylindrical portion 18 is held in the semi-circular groove 22 by a circular plate 23 which is formed with a semi-circular depression 24

extending transversely across the same and embracing the lower half of the cylindrical portion 18 of the tubular arm. Screws 25 extend up through holes in the plate 23 and thread into tapped holes in the insulating body portion of the plug 12. The upper half

80 of the cylindrical portion 18 is slotted longitudinally to permit the insertion into the tubular arm of the wires 26 and 27 which extend down from the terminals in the body portion of the plug. Each of

85 these terminals consists of a pair of spring jaws—adapted for the reception of prongs on the cooperating cap of the plug in the ordinary usage thereof—and the conducting wires 26 and 27 are connected to these terminals in any suitable manner. The particular construction of this type of plug is

90 well known in the art. It will be noted that the ends of the longitudinal slot in the cylindrical portion 18 where the wires 26 and 27 enter the same are cut down to either

95 side so as to permit a large degree of angular movement of the arm 14 without pinching the wires.

Figure 12 is a side elevational view of an extensible type of depending arm, also adaptable to either of the above constructions.

Figure 13 is a reduced elevational view illustrating the combined grouping of a reflector and shade on the adapter for the purpose of producing a soft, diffused, indirect light.

100 The form of adapter illustrated in Figures 1 and 2 comprises a plug member 12 which is adapted to be screwed into the outlet socket 13 of a conventional form of lighting fixture. I have shown the standard Edison type of plug and socket as being the preferred form because of certain advantages which can be secured by the same.

105 Pivotedly supported on the bottom of the plug 12 and depending therefrom is a tubular supporting arm 14 of curved goose-neck formation. The tubular arm 14 carries at its lower end the combined light and attachment

110 sockets 15 and 16, the latter socket forming a terminal connection for the appliance circuit. These sockets comprise two concentric portions, namely, the outer shell or ring and a central stud or plate as is well

115 understood by those skilled in the art. This tubular arm preferably consists of a section of brass tubing which is flattened in the curved portion intermediate the plug 12 and sockets 15—16 so as to present a minimum

120 thickness of tube to the rays from the light 17 and thereby reduce the extent of shadow cast by the tubular arm. As shown in Figure 3, the horizontal pivotal portion 18 of the tube is formed cylindrical, and is provided with two collars 19 and 20. I con-

125 template as the preferred construction the employment of a standard construction of plug 12, modifying this construction of plug only to a slight degree in adapting it to the present construction. The under face of the 120

125 plug member 12 is grooved transversely as indicated at 22 to accommodate the cylindrical portion 18 of the tubular arm, the two collars 19 and 20 embracing the sides of the body portion of the plug. The cylindrical portion 18 is held in the semi-circular groove 22 by a circular plate 23 which is formed with a semi-circular depression 24

130 extending transversely across the same and embracing the lower half of the cylindrical portion 18 of the tubular arm. Screws 25 extend up through holes in the plate 23 and thread into tapped holes in the insulating body portion of the plug 12. The upper half

135 of the cylindrical portion 18 is slotted longitudinally to permit the insertion into the tubular arm of the wires 26 and 27 which extend down from the terminals in the body portion of the plug. Each of

140 these terminals consists of a pair of spring jaws—adapted for the reception of prongs on the cooperating cap of the plug in the ordinary usage thereof—and the conducting wires 26 and 27 are connected to these terminals in any suitable manner. The particular construction of this type of plug is

socket from the tubular arm 14 is extended through a hole in the insulating sleeve 32 and has suitable electrical connection with the shells 34 and 35. Encircling the line of juncture of the two insulating sleeves 32 and 33 is a beaded conducting ring 36, to which the other of the conducting wires entering the socket is connected. This conducting ring has soldered thereto two radially extending spring contacts 37 and 38. These spring contacts enter the sockets at diametrically opposite points on about the same level, and at these points the threaded shells 34 and 35 are slotted or cut away so as to avoid contact with the contact members. The end of the spring contact 37 is bowed upwardly to engage with the tip contact of the light. The spring contact 38 is bowed downwardly to engage with the tip terminal of the attachment plug, and the end of this spring contact is bent upwardly as indicated at 39 so as to form a raising extension for engaging the upper contact spring 37 and raising it into contact with the cooperating tip terminal of the light. The two contacts 37 and 38 are so positioned in the double socket that normally the upper contact 37 will be out of engagement with the tip of the light, when the latter is screwed down as far as it will go. The light is included in circuit by screwing up the upper portion of the attachment plug 41 into the attachment socket 16. The tip terminal of this attachment plug engages its respective spring contact 38 and thrusts the latter upwardly during the continued threading motion of the plug, whereby the raising extension 39 on the contact engages the upper spring contact 37 and raises the same into contact with the tip terminal of the light. The attachment plug thus performs the switching function for the light socket in an exceedingly simple and effective manner. I do not intend to limit the invention to employment of this switching operation as it is a function which I dispense with in certain forms by making the contact for the lamp base engage the tip contact of the lamp independently of the plug. The attachment plug 41 is preferably a two-part pull plug consisting of the upper threaded portion and the lower pull portion having prong terminals adapted to be inserted into socket terminals in the body of the threaded portion of the plug. The upper threaded portion of the plug can thus be retained in the socket 16 at all times to conveniently serve as the switching medium for the light socket 15.

The practical use of this form of adapter is illustrated in Figures 1 and 2. In Figure 1, I have illustrated the adapter as supported in the socket of a depending chain fixture. In this figure I have also illustrated the device as arranged for an indirect lighting effect. The shade or reflector 44 is supported upon the combined sockets 15-16 by a conventional form of clamp 45. The reflector unit 44 may be the direct lighting shade or reflector which was originally in use on the socket of the chain fixture--being simply inverted on the adapter to afford an indirect reflection--or it may be any special form of reflector. The clamp 45 is of conventional pattern, being capable of mounting on the standard socket 16 and receiving any standard size of shade or reflector. In Figure 13 I have illustrated an outer shade 47 mounted outside of the reflector 44, this outer shade being preferably composed of silk, parchment or other translucent material now in vogue. The combined shade and reflector perform a very desirable function in the indirect lighting scheme, the reflector 44 diffusing the lateral and downward rays, and the shade 47 "softening" these rays so that the resulting light is of a soft pleasing character. The shade 47 may be mounted by providing the wire frame thereof with members engaging over the upper edge of the reflector 44.

It will be noted from Figure 1 that the light 17 is aligned coincident with the axis of the fixture socket 13 whereby the original grouping of the lights for the most effective light distribution is not affected. The attachment circuit, which is represented by the cord 46 leading from the attachment plug, may be extended to an electric toaster, a coffee percolator, a sewing machine motor, or any other electrical attachment. It will, of course, be obvious that a light might be substituted for the attachment plug 41 in circumstances where more light might be desired, and it is to be understood that in the appended claims the reference to "light" socket and "attachment" socket is solely for the convenience of reference. Figure 2 shows the adapter supported in an inclined fixture socket, and illustrates the particular utility of the pivotal connection of the tubular supporting arm 14. In this figure the shade has been removed to obtain a direct lighting effect, although such removal is not necessary. In each case, the adapter may be used with or without the shade.

The modified construction illustrated in Figure 6 employs a rigid plug 48 which is fixedly secured to the upper end of the tubular depending arm 14^a. The plug 48 is preferably of standard construction and is supported in a cylindrical metallic shell 49 to which the upper end of the goose-neck arm 14^a is brazed. The conducting wires in the arm 14^a are connected to the terminals of the plug 48 in an obvious manner and I shall not therefore describe the detailed construction of the plug. The two co-extensive sockets 15 and 16 at the lower end of the supporting arm 14 are, for the greater por-

tion, constructed similarly to the sockets 15 and 16 of the previous embodiment. In the present form, however, the two inner threaded shells 51 and 52 are spaced apart by two fiber discs 53 and 54 which set into the expanded portions of the outer shells. The two fiber washers 53 and 54 are in turn spaced by intervening spacing members 55 of insulation, through which extend bolts 56 connecting the members 53, 54 and 55 together. The threaded shells 51 and 52 have inwardly turned flanges or bottom portions through which the bolts 56 extend, and the engagement of the heads of these bolts and the nuts 56' thereof with these flanges or base portions electrically connects the two shells together. The two fiber discs 53 and 54 have central openings 57—57—the base portions of the threaded shells 51 and 52 having similar openings matching therewith—and lying in these openings is a central movable contact 58. As shown in Figure 9, this central contact 58 is carried by a flat spiral spring 59, the outer end of this spiral spring being secured to the lower fiber disc 54 by a screw 61. One of the connecting wires entering the socket has connection with the shells 51 and 52 in the usual manner, and the other conducting wire has connection with the spiral spring 59, preferably at the screw 61. The spiral spring 59 normally retains the central contact 58 in a lowered position as indicated in Figure 6, whereby the light 17 is normally out of circuit. As described in connection with the previous embodiment, by screwing the attachment plug up into the lower socket 16 the central contact 58 is raised upwardly into the upper socket 15 and thus makes contact with the tip terminal of the light 17, although this may also be modified.

As shown in Figures 1 to 6, and 8 to 9, the central contact which serves the function of a switch for cutting out the lamp 17 lies nearer to the outer end of the lower socket shell than it does to the upper, so that contact will first be made by the plug, such as the plug 41 shown in Figure 4, and if this plug is then further threaded into the socket, the central contact will engage the central contact of the lamp 17.

As shown in Fig. 4 the arm 38, 39 has been forced inwardly by the plug 41 to an intermediate position.

In Figure 7 I have illustrated a modified arrangement of adapter which is devised to support the light 17 in inverted position. This construction comprises a combined plug 62 and socket 63 of standard construction, to which is secured the depending tubular arm 14'. This fitting 62—63 is preferably of the type having a laterally extending socket opening into the side of the fitting for current-tap connection, and in adapting this fitting to the present construc-

tion the goose-neck arm 14' is simply secured over the lateral opening provided in the outer shell for the lateral socket. The insulating block in this construction of fitting is provided with two current tap connections, one of which is indicated in dotted lines at 64, and to these current tap connections are secured the ends of the wires leading down through the tubular arm 14'. The lower end of the tubular arm 14' is curved back into the axis of the adapter, and on this lower end is supported the socket member 65 of a pull type of plug. The lower co-operating half 66 of the plug is provided with two prong contacts 67 which insert into similarly formed sockets in the bottom of the plug portion 65. The cord 68 extends to the electrical attachment, which may be of any desired character. This construction of adapter is of particular advantage for direct lighting effects as it may be made to very conveniently support a direct lighting shade or reflector lying outside of the arm 14'.

The bottom parts 41 and 66 of the separable connector plugs may be provided with prongs which may be turned to adapt them for parallel or aligned slots. Such fittings are now sold under the trade names of "Paraline" and "Adaptacap".

In Figure 8 I have illustrated another modified form of adapter having a pivotal support for the depending arm 14" and a pull-chain type of socket for the light 17. The plug 71 for screwing into the service outlet is secured to a spherical shell 72 which has pivotal connection with a semi-spherical shell 73 on the upper end of the tubular arm 14". The lower shell 73 is provided with upwardly extending lugs 74 at diametrically opposite points through which extend pivot screws 75 which thread into the upper shell 72. The lower portion of the upper shell 72 extends down into the shell 73 a slight distance so as to maintain the shells closed in the various angular positions of the plug 71. A spur 76 is preferably struck out of the body of the upper shell 72 so as to engage the upper edge of the lower shell 73 and limit the angular motion of the shells in one direction. The tubular arm 14" is formed co-extensive with an opening in the bottom of the lower shell 73, being secured to the shell in any suitable manner, and the wires 26 and 27 extend down from their terminals in the plug 71 and enter the tubular arm 14". The lower end of the tubular arm carries a pull-chain socket 77 of conventional construction having the customary pull-chain 78 for controlling a rotary switch in the socket. The lower end of the socket 77 extends into a sleeve 79, to which it is secured by the provision of short spurs struck out from the wall of the socket and engaging in depressions in the inner

wall of the sleeve 79, as will be apparent to one skilled in the art. The lower portion of the sleeve 79 is extended outwardly to accommodate an inner sleeve of insulation 81, and fitting within this insulating sleeve is the socket member 82 of a conventional form of two-part pull plug, such as shown at 65 in Figure 7. This plug member is retained in the sleeve 79 by an inwardly spun flange 83 on the lower end of the sleeve. The co-operating cap portion 84 of this plug is provided with two contact prongs 85 which are adapted to be inserted into suitable sockets in the insulating body of the plug member 82. These socket terminals have suitable parallel connection with the terminals of the pull-chain socket 77. At 86 I have illustrated one of the terminal clips which connect with these socket terminals and which are in turn connected with the terminals of the socket 77 through wires 87. An outer flange or extension 88 projects upwardly from the sleeve 79 and is formed with an outwardly curved lip within which rests the lower edge of an indirect reflector or shade 89. A circular detent spring 90 is confined in slotted openings in the upper edge of the flange 88 and supports the reflector 89 by engaging over the bead 91 on the lower edge thereof. This reflector may also be provided with an outer shade as illustrated in Figure 13.

In Figures 10 and 11, I have illustrated a hinged construction of depending arm, which may be embodied in either of the preceding structures. This hinged construction is arranged by dividing the depending arm at an intermediate point into upper and lower tubular sections 92 and 93. The end 40 of the upper section 92 is bifurcated and has its two fork arms spread outwardly as indicated at 94 to embrace the end of the lower section 93. The end of the lower section is preferably slotted as indicated at 95 to lend resiliency to the hinge joint. A hinge pin 96 is passed through aligned apertures in the slotted ends of the two sections, and a knurled clamping nut 97 is threaded over the end of the hinge pin to impose sufficient tension on the hinge joint to retain it in any of its various angular positions. The conducting wires 26 and 27 are extended around the hinge pin 96 in passing from one section of the tubular arm to the other. The particular utility of this hinge joint in the depending arm resides in the ability to adjust the position of the double socket 15-16 to any desired angle, whereby the adapter may be inserted in an inclined socket as indicated in Figure 2 and the light in the socket maintained in vertical position, or whereby the light may be variously inclined for different and more effective lighting schemes.

In Figure 12 I have illustrated an extensible construction of depending arm which

may also be embodied in either of the preceding forms of adapters. In this construction the depending arm is divided into upper and lower sections 98 and 99, the adjoining ends of which are formed straight and are 70 provided with threads of opposite lead. An adjusting sleeve 100, having cooperating internal threads of opposite lead, screws over the threaded ends of the sections 98 and 99. By rotating this sleeve relative to the arm 75 sections 98 and 99 the two sections may be separated or drawn together, thereby affording an extensible adjustment in the depending arm. Lock nuts may be provided on the threaded arm sections 98 and 99 to engage 80 with the ends of the adjusting sleeve 100 and clamp the same in any adjusted position. The conducting wires are passed through the sleeve 100, and are arranged with a certain amount of slack to permit the extensible adjustment. This extensible adjustment enables the double socket 15-16 to be drawn to or separated from the plug end of the adapter and thus permits of the convenient use of large or small lights in the 85 double socket. It, moreover, permits of various adjustments incident in adapting shades and reflectors to the device.

I do not intend to be limited to the precise details shown and described. 95

I claim:

1. In an adapter, the combination of a standard plug, a first standard socket, a second standard socket, supporting means depending from said plug and extending 100 downwardly for the support of one of said sockets, said supporting means consisting of a single rod lying wholly at one side of the plug and the sockets, said sockets being adapted to provide outlets for a plurality of 105 electrical devices and being arranged substantially in axial alignment with said plug.

2. In an adapter of the class described, the combination of a plug adapted for connection in a standard outlet socket, a tubular arm pivotally connected to said plug and depending therefrom, an attachment socket carried on the end of said tubular arm, said socket facing downwardly, a light socket supported by said tubular arm and facing 115 upwardly, and an electrical conductor extending through said tubular arm and electrically connecting said plug with both of said sockets.

3. In combination, a plug adapted for insertion in an outlet socket, a supporting member having connection with said plug and extending substantially below the same, a pair of sockets carried on the end of said supporting member, and a shiftable contact 120 in one of said sockets adapted to be moved into operative position by a plug in the co-operating socket.

4. In an adapter, the combination of a plug having terminals therein, a tubular 130

arm pivotally bearing in a groove in said plug, means for pivotally retaining said tubular arm in said groove, a conducting wire having connection with one of said plug terminals and extending into said tubular arm, a pair of sockets supported on the end of said tubular arm, said sockets comprising socket contacts connected in parallel, said conducting wire being connected 10 to one of said contacts.

5. In combination, a plug adapted for insertion in an outlet socket, a depending arm of relatively small diameter with respect to the diameter of the plug, a pair of sockets carried on the lower end of said arm and connected in parallel to said plug, and a pivotal connection between said arm and said plug to permit relative angular motion therebetween, the axis of the pivotal connection lying substantially at right angles to the axis of the plug.

6. In a device of the class described, the combination of a plug member adapted for engagement in an outlet socket, a tubular depending arm having connection with said plug member and extending substantially below the same, a double socket member carried on the end of said tubular arm, a conducting wire extending from said plug member to said double socket member through said tubular arm, and a hinge joint for permitting relative angular adjustment between said plug member and said double socket member.

35. 7. In an adapter for converting a direct lighting fixture into an indirect lighting fixture, the combination of a plug member adapted for insertion into the socket of the direct lighting fixture, a supporting member extending from said plug member, a socket member carried by said supporting member, and an indirect shade or reflector open at its top supported on said socket member and adapted to shield a lamp in said socket member from direct vision.

40. 8. In an adapter for converting a direct lighting fixture into an indirect lighting fixture, the combination of an Edison screw plug member adapted for insertion into the socket of the direct lighting fixture, a depending arm extending downwardly from said plug member, a socket member carried on the end of said depending arm for receiving the light, and means supported on said socket member for receiving an indirect shade or reflector substantially closed at the bottom and open at the top for shielding a lamp in said socket from direct vision.

55. 9. In an adapter for converting a direct lighting fixture into an indirect lighting fixture, the combination of a plug member adapted for insertion into the outlet socket of the direct lighting fixture, a tubular arm of relatively small diameter depending from said plug member, a socket member carried

by said tubular arm and having electrical connections with said plug member through an electrical conductor extending through said tubular arm, clamping means on said socket member, and an indirect shade or reflector open at its top, supported by said clamping means said arm lying inside of the shade.

10. In an adapter for converting a direct lighting fixture into an indirect lighting fixture, the combination of a plug member adapted for insertion into the socket of the direct lighting fixture, a tubular arm extending substantially downwardly from said plug member, a double socket member carried on the end of said tubular arm, said double socket member comprising a light socket and an attachment socket, both of said sockets having electrical connection with said plug member, through an electrical conductor extending through said tubular arm, and clamping means carried by said double socket member adapted to support an open topped indirect shade or reflector about said double socket member to shield a lamp in said light socket from direct vision.

11. In combination, a plug member adapted for insertion in an outlet socket, a supporting member extending from said plug member, a socket member carried by said supporting member and adapted to receive a light, an indirect reflector supported adjacent said socket member for shielding said light from direct vision, and an outer shade cooperating with and mounted on said indirect reflector.

12. In an adapter for converting a direct lighting fixture into an indirect lighting fixture, the combination of a plug member adapted for insertion into the outlet socket of the direct lighting fixture, a depending arm extending downwardly from said plug member, a socket member carried by said depending arm and adapted to receive the light, an indirect reflector supported on and in proximity to said socket member for shielding said light from direct vision, and an outer shade encircling said indirect reflector and cooperating therewith in distributing and diffusing the light rays.

13. An article of manufacture comprising a pair of sockets facing in opposite directions and axially in line with each other, a plug axially in line with the sockets and located above the same, a rigid arm connecting the plug with the said sockets, said sockets comprising a pair of shell members and a common central contact member, said plug comprising a shell member and a central contact member, said central contact members and said shell members being connected together electrically.

14. In a device of the class described, a standard Edison plug for insertion in a standard direct lighting Edison socket, a

- standard Edison socket in substantial alignment with the plug and opening upward and adapted to support a standard illuminating lamp below the plug, a relatively small diameter tubular arm between the plug and said socket, said arm being bent to clear the lamp, and a bowl-shaped shade flaring upwardly supported on said socket and surrounding said arm and adapted to shield the lamp from direct vision.
15. In an adapter, in combination with a standard light socket, supporting means adapted for attachment to said socket, a second socket on said supporting means spaced from and opening back toward said first socket, and a shade mounted on said second socket with its large end opening toward said first socket and having its small end substantially closed.
20. 16. In an adapter, in combination with a standard light socket, supporting means adapted for attachment to said socket, a second socket on said supporting means spaced from and opening back toward said first socket, and a third socket positioned back-to-back with said first socket, said supporting means including a pivotal connection permitting movement of said second socket about an axis perpendicular to the axis of the first socket. 25
17. In an adapter, in combination with a standard light socket, supporting means adapted for attachment to said socket, a second socket on said supporting means spaced from and opening back toward said first socket, and a pivotal connection forming part of said supporting means and permitting movement of said second socket about an axis perpendicular to the axis of the first socket. 30
